UNITED STATES PATENT OFFICE.

OSCAR E. WAIT, OF SPRINGFIELD, VERMONT.

DESIGN FOR A HEATING-DRUM.

SPECIFICATION forming part of Design No. 31,609, dated October 3, 1899.

Application filed September 9, 1899. Serial No. 730,029. Term of patent 14 years.

To all whom it may concern:

Be it known that I, OSCAR E. WAIT, a citizen of the United States, residing in Springfield, in the county of Windsor and State of Vermont, have invented and produced a new and original Design for a Heating-Drum, of which the following is a specification, reference being had to the accompanying drawing, in which the only figure is a perspective view 10 of a heating-drum, showing my new design.

As shown in the drawing, the body A of the drum is of a hexagonal form in cross-section. At each end there is a short cylindrical portion 1, having a bead 2 at its inner 15 end, and between the said bead and body of the drum there is a short pyramidal portion 3, with beads 4 at the junction with the body portion. Each of the sides of the hex-

agonal body 4 is provided with a series of holes 5, arranged in pairs, the holes on each side 20 being a little higher than the holes in the next adjacent side toward the left, thereby making the series of holes extend spirally around the said body. Between each pair of holes, near their lower edge, on three of the six hexagonal sides there is a knob-shaped projection 6, as shown.

Having described my invention, what I claim as new, and desire to secure by Letters Patent, is—

The design for a heating-drum as herein shown and described.

OSCAR E. WAIT.
